(57) **CLAIM**

The ornamental design for a toy, as shown and described.

DESCRIPTION

FIG. 1 is a front, left and top perspective view of a toy, showing my new design;

FIG. 2 is a rear, right and bottom perspective view thereof;

FIG. 3 is a front view thereof;

FIG. 4 is a rear view thereof;

FIG. 5 is an enlarged top side view thereof;

FIG. 6 is an enlarged bottom side view thereof;

FIG. 7 is a left plan view thereof;

FIG. 8 is a right plan view thereof; and,

FIG. 9 is an alternative perspective view shown in an open state.

The broken lines shown in the drawings illustrate portions of the toy that form no part of the claimed design.

1 Claim, 9 Drawing Sheets
